ARTIFICIAL CHRISTMAS TREE OR SIMILAR ARTICLE

James S. Farquhar, Los Angeles, Calif.

Application September 18, 1959, Serial No. 57,608

Term of patent 14 years

(Cl. D29—1)

Fig. 1 is an elevation view of an artificial Christmas tree or similar article showing my new design;

Fig. 2 is a top plan view; and

Fig. 3 is a bottom plan view thereof.

I claim:

The ornamental design for an artificial Christmas tree or similar article, substantially as shown.
